COMBINATION REFUSE RECEIVING RECEPTACLE AND SUPPORTING RACK
Clarence Smith, 318 N. C St., Wellington, Kans.
Filed Oct. 3, 1963, Ser. No. 313,512
5 Claims. (Cl. 220—18)

This invention relates to a refuse receiving receptacle and, more particularly, but not by way of limitation, to the refuse receiving receptacle and a novel rack which is used to pivotally support the receptacle so that it may be more easily filled, and more easily emptied after it has become full.

In disposing of domestic trash, garbage and other refuse, certain well known problems exist relative to maintaining sanitary conditions around the receptacles in which such refuse is placed pending removal by the municipality. These problems include ease or convenience of emptying the receptacles when the refuse is collected by the municipality, preventage of rusting or deterioration of the receptacle in which the refuse is located, etc. Most frequently, garbage, trash and other heterogeneous waste materials are placed by residents and business establishments in large cylindrical cans or drums pending collection or removal of the cans by the municipal employees charged with this duty. Varying methods are utilized by municipalities for transferring the refuse from the drums or cans to garbage trucks or other collection vehicles. However, in many of these methods, the garbage or trash is transferred from the drum or can in which it is deposited by the homeowner to other receptacles possessed by the city employees charged with garbage collection. In effecting the transfer of the trash or garbage, spillage frequently occurs with the result that untidy and unsanitary conditions result in the locale of the homeowner's garbage receptacle, which must therefore frequently be cleaned up and policed. Moreover, in many instances, due to the contents or construction of the drums or cans in which the garbage is stored while awaiting pickup by the city employees, the transfer of the contents of the can to the receptacles possessed by the municipal employees is quite difficult due to the heavy weight and cumbersome nature of the cans. Also, in some instances, the cans are retained in or on racks in a semipermanent fashion which, due to the rack construction, makes their removal therefrom difficult and time-consuming.

In addition to the various difficulties and problems experienced in the collection of refuse and garbage by municipalities, it is common knowledge that such cylindrical or drum-type garbage receptacles are the object of attacks by dogs, cats or other domestic animals, and also frequently become infested with insects, rodents and other undesirable animal life. To the end of more efficiently protecting the garbage receptacles and their contents against attacks by domestic animals and infestation by vermin, numerous constructions of garbage cans and, particularly, racks or stands for supporting these cans have been developed which undertake to more firmly secure the lids on the cans, or to more stably support the cans against attacks by animals, and to support the cans spaced from the ground so that accessibility to rodents, roaches and other crawling animals is reduced.

The present invention comprises an improved combination trash or garbage receptacle and supporting rack which permits many of the hereinbefore described problems and difficulties to be overcome, yet which is relatively economical in construction and characterized by a long and trouble-free service life. In one of its broader aspects, the invention comprises a pair of upstanding rigid members which are spaced from each other and which pivotally support between them a garbage receptacle so that the lower end of the receptacle is spaced well above

2

the ground, and so that the receptacle is balanced to pivot easily from a refuse receiving position to a refuse dumping position without the application of a large amount of force in order to effect such pivotatation. At their upper ends, the rigid upstanding members carry a stop means which serves to reinforce the upstanding members, and to form a framework therewith to prevent pivotatation of the refuse receptacle past a certain position as it moves from a dumping position to a trash receiving position. The rigid upstanding members which pivotally support the refuse receptacle are each pivoted to a horizontal platform which rests upon the ground so that these members may themselves be pivoted about a horizontal pivotal axis to increase the ease with which all of the contents of the refuse receptacle may be removed.

15 In one of its embodiments, the invention further includes a semicylindrical guide or sleeve means which is slidably positioned concentrically within a cylindrical refuse receptacle mounted in the manner hereinbefore described, with such sleeve means being slidable between an extended position projecting outwardly from the open end of the refuse receptacle, and a retracted position in which it is retracted into the refuse receptacle to permit ready access to the entire area of the open mouth of the receptacle.

20 25 The thus generally described structure which is embodied in the present invention provides a combination supporting rack and refuse receptacle which may be employed to permit garbage, trash or other refuse to be easily deposited in the receptacle at all times prior to dumping.

30 It is an object of the present invention to provide an improved combination refuse receptacle and rack for supporting the same.

Another object of the present invention is to provide 35 a drum-type garbage receptacle for receiving table scraps, trash, garbage and heterogeneous refuse, which receptacle is supported in a rack in a manner which permits it to be more easily divested of its contents in the course of the usual refuse pickup runs by municipal employees.

40 An additional object of the present invention is to provide a cylindrical garbage receptacle having an open mouth at one end thereof which is maintained in an accessible position to facilitate the transfer of refuse to the receptacle.

45 Yet another object of the present invention is to provide a refuse receptacle which is pivotally and stably supported on a rack and spaced above the ground to prevent rodents, vermin and domestic animals from entering the can, or from overturning the can and rack.

50 Yet another object of the present invention is to provide a refuse receptacle into which refuse may be placed and from which refuse may be transferred to another receptacle without scattering or inadvertent deposition of the refuse on the ground surrounding the receptacle.

55 Another object of the present invention is to provide a rack or stand for pivotally supporting a cylindrical refuse receptacle, which rack is sturdy, yet economical in construction.

60 A further object of the present invention is to provide a combination garbage receptacle and rack cooperating with and supporting the receptacle, which combination is relatively inexpensive to construct, and is characterized by a long and trouble-free operating life.

In addition to the foregoing described objects and advantages of the invention, other objects and advantages will become apparent as the following detailed description of the invention is read in conjunction with a perusal of the accompanying drawings which illustrate the invention.

70 In the drawings:

FIGURE 1 is a view in elevation of the refuse recep-

tacle and its supporting rack. In FIGURE 1, the refuse receptacle is shown in its refuse receiving position with the lid in place.

FIGURE 2 is a view in elevation similar to FIGURE 1, but showing the refuse receptacle pivoted downwardly to discharge its contents into a transfer container.

FIGURE 3 is a view in elevation similar to FIGURES 1 and 2, but showing the refuse receptacle positioned relative to the supporting rack in the same manner as disclosed in FIGURE 2, and showing the supporting rack pivoted about a horizontal axis to permit a more complete discharge of the contents of the refuse receptacle.

FIGURE 4 is a view in elevation taken at 90° to the elevational view shown in FIGURE 1 and illustrating the refuse receptacle and its supporting rack as they appear when in the refuse receiving position.

FIGURE 5 is a longitudinal sectional view taken through the center of the refuse receptacle along the longitudinal axis thereof. The receptacle supporting rack is not illustrated.

FIGURE 6 is a sectional view taken along line 6—6 of FIGURE 1.

FIGURE 7 is a detail view of the latching arrangement used to secure the refuse receptacle of the present invention in its refuse receiving upright position on its supporting rack.

Referring now to the drawings in detail, and particularly to FIGURE 1, the novel refuse receiving and storage structure of the present invention comprises a horizontal base structure designated generally by reference character 10 which includes a pair of parallel runners 12 (see FIGURE 6) which may suitably be constructed of angle iron. The runners 12 are interconnected and braced by suitable cross members 14.

The horizontal base structure 10 supports a pair of horizontally spaced upright members 16 which, in one embodiment of the invention may assume the form of a regular trapezoid formed by converging side pieces 18 interconnected intermediate their length by a horizontal brace 20. The rigid upright members 16 may be interconnected by one or more horizontal cross pieces 22 as shown in FIGURE 4. The rigid upright members 16 each support at their upper ends, a suitable trunnion or bearing supporting member 24, each of which, as illustrated in FIGURES 4 and 6, supports a trunnion or bearing socket 26. In the embodiment of the invention illustrated in the drawings, the trunnion supporting members 24 are angle iron strips to which the trunnions 26 are secured in the manner illustrated in FIGURE 6.

The rigid upright members 16 are spaced from each other by a distance slightly greater than the diameter of a refuse receptacle which it is desired to pivotally support on the upright members. A cylindrical drum or can 30 having a suitable lid 32 provided therefor is pivotally suspended between the rigid upright members 16 in the manner illustrated in FIGURES 1, 4 and 6. Support for the refuse receptacle 30 is provided by bolting or otherwise suitably securing to the receptacle on opposite sides thereof, a pair of journal blocks or hubs 34. The journal blocks 34 each rotatably receive one end of a short stub shaft or axle 36 which extends at its other end through the respective trunnion supporting member 24 and into the respective trunnion block 26. Axial movement of the stub shafts 36 relative to the journal blocks 34 and trunnion blocks 26 is prevented by any suitable means, such as by inserting a pin 40 through one end of the shaft into the trunnion blocks 36, as illustrated in FIGURE 6. It will be perceived that, in the illustrated arrangement for supporting the receptacle 30 on the rigid upright members 16, the receptacle is free to pivot about the horizontal pivotal axis formed by the stub shafts 36 on either side thereof.

The location of the journal blocks 34 on the receptacle 30 is of considerable importance, and is believed to be a novel feature of the present invention, particularly

when considered in conjunction with other structural details hereinafter described. Thus, it will be noted in referring to FIGURE 1, that the journal blocks 34 are positioned slightly below the center of the receptacle 30 as measured along its vertical axis. Stated differently, the journal blocks 34 should be positioned sufficiently toward the bottom of the receptacle 30 that the center of gravity of the empty receptacle 30 when it occupies the position shown in FIGURE 1 acts downwardly in a line which passes to the right of the pivotal axis of the receptacle. With the receptacle mounted in this way, the receptacle constantly tends to pivot downwardly toward the position shown in FIGURE 2 and can be retained, even when empty, in the FIGURE 1 position only through the use of the latching means 42 which is hingedly connected to the side of the receptacle 30 near the top thereof and functions to latch the receptacle 30 to a projection of the supporting rack when the receptacle is in its FIGURE 1 position.

The latching means 42 comprises a flat plate 44 having a projection 46 extending substantially normal thereto, which projection may be hooked over the bight 48 of a generally U-shaped bracket 50 which is best seen in FIGURE 4. The U-shaped bracket 50 includes, in addition to the bight 48, a pair of legs 52 which are welded or otherwise suitably secured at their lower ends to the upper ends of the rigid upright members 16, and preferably to the trunnion supporting member 24. The manner in which the latching means 42 engages the bight 48 of the U-shaped member 50 when the receptacle 30 is in its refuse receiving position as shown in FIGURE 1 is best illustrated in FIGURE 7.

In order to permit the more efficient displacement of the contents of the refuse receptacle 30 therefrom during pickup by municipal employees, the receptacle supporting rack is pivotally connected to the horizontal base 10 to permit the rack to be pivoted in the manner illustrated in FIGURE 3. This construction, in one embodiment of the invention, is provided by journaling one of the legs 18 of each of the rigid upright members 16 on a horizontal bar 60 which is secured at its opposite ends to the angle iron runners 12. As an alternative construction, the legs 18 may instead be secured to the horizontal bar 60 and this bar journaled at its opposite ends in the runners 12.

In order to facilitate the discharge of the contents of the refuse receptacle 30, a receiving container, such as a rectangular box 62, as illustrated in FIGURES 2 and 3, is placed beneath and to one side of the receptacle. A retractable guide means, such as the semicylindrical sleeve 64, is mounted concentrically in the receptacle 30. The semicylindrical sleeve 64 is retractably mounted in the cylindrical refuse receptacle 30 in the manner most clearly illustrated in FIGURES 5 and 6. As will be discerned in referring to FIGURE 6, the semicylindrical sleeve 64 is substantially complementary in configuration to the wall of the refuse receptacle 30 so that it does not substantially lessen the total capacity of the receptacle 30 when the sleeve is retracted therein in the manner illustrated in FIGURE 5. The retractable sleeve 64 is gravity actuated in its sliding movements relative to the receptacle 30, and moves in a pair of vertically extending angle iron tracks 66 which are welded or otherwise suitably secured to the inner walls of the receptacle 30 and extend parallel to the longitudinal axis thereof. The longitudinal edges 67 of the semicylindrical retractable sleeve 64 ride on the angle iron tracks 66 during sliding movement of the sleeve in and out of the receptacle 30. A stop member 68 is secured to each of the tracks 66 at a point therealong which is preferably about two-thirds of the distance from the innermost end of the respective track 66 to that end which is adjacent the top of the refuse receptacle 30. The stop members 68 cooperate with stop members 70 which are welded or otherwise suitably secured to the sleeve 64 at the innermost end thereof, and adjacent the

longitudinal eages 67 thereof so that the sleeve-secured stop members 70 engage the stop members 68 to limit the travel of the sleeve 64 in the tracks 66. The sleeve 64 is thus prevented from being lost from the receptacle 30 when the receptacle is pivoted to the position shown in FIGURES 2 and 3 of the drawings.

A small flange 72 is secured to the inner wall of the refuse receptacle 30 at a position therein which will permit the retractable sleeve 64 to be fully retracted within the receptacle in the manner shown in FIGURE 5. The flange 72, of course, serves to limit movement of the sleeve 64 downwardly in the receptacle when it gravitates into the receptacle as the receptacle is pivoted upwardly to the position shown in FIGURE 1.

Operation

With the supporting rack and refuse receptacle 30 in the position illustrated in FIGURE 1, the empty refuse receptacle is balanced on the rack so that if the latch means 42 is released from engagement with the bight 48 of U-shaped member 50, the receptacle will pivot downwardly to the position shown in FIGURE 2. When the receptacle 30 is in use for receiving and storing the garbage, trash and other refuse, the latch 42 will generally be maintained in the engaged status illustrated in FIGURE 1. It will be observed that the mouth or open end of the receptacle 30 is disposed for easy access in being tilted at the illustrated angle. Moreover, its entire contents can usually be viewed by removing the lid 32. This is sometimes helpful in the event that one wishes to recover something inadvertently discarded, or wishes to better arrange or pack the contents of the receptacle 30.

As refuse is deposited in the receptacle 30, it accumulates initially in the lower portion thereof. Very little refuse need be added to the receptacle in order to shift the center of gravity thereof so that the center of gravity acts through the pivotal axis of the receptacle 30, or along a line which is disposed to the left of the pivotal axis as viewed in FIGURE 1. Thus, during initial depositions of garbage and refuse in the receptacle 30, the balance of the receptacle 30 is shifted so that, even though the latch means 42 be inadvertently or mischievously disengaged, the receptacle 30 still will not tilt downwardly and discharge its contents. A safety factor is thus afforded during a substantial portion of the time during which refuse is accumulated in the receptacle 30 against the inadvertent or mischievous displacement of the latch means 42 by the homeowner or by vandals or other mischievous persons.

As the receptacle 30 becomes filled with refuse, the center of gravity is again shifted to the right as viewed in FIGURE 1 so that the receptacle 30 develops a tendency to pivot downwardly when the latch means 42 is released. When the receptacle 30 has been completely filled, or, when the municipal employees charged with the collection of refuse desire to empty the receptacle 30, the latch means 42 may be disengaged by pivoting the plate 44 upwardly. The receptacle 30 will then automatically pivot downwardly to the position illustrated in FIGURE 2. The balance of the receptacle 30 is such that the downward pivoting movement of the receptacle may be retarded by the application of a small retarding force as may be applied by the use of one hand by the refuse collector. As the receptacle 30 passes a position in which its longitudinal axis is substantially horizontal, the retractable sleeve 64 commences to move out of the receptacle and eventually reaches the position shown in FIGURE 2. In this position of the retractable sleeve 64, further movement of the sleeve 64 out of the receptacle 30 is prevented by abutment of the stop members 70 against the stop members 68 on the tracks 66.

It will also be noted that when the receptacle 30 has reached the position shown in FIGURE 2, further downward pivotatation of the receptacle 30 is prevented by abutment of the lower end of the receptacle 30 against the

bight or web 48 of the U-shaped bracket 50. This is a safety measure which prevents over-pivotatation of the receptacle 30 with a concurrent failure to accurately deposit all of the contents of the receptacle in a box or other receiving member positioned therebelow in the manner illustrated in FIGURE 2.

As is well known, household refuse frequently includes gummy or sticky materials and liquids which are adhesive in nature. It is therefore frequently rather difficult to remove by gravity the entire contents of the receptacle 30, particularly when the receptacle 30 is inclined at no greater angle than that which is illustrated in FIGURE 2. To the end, therefore, of permitting substantially all of the contents of the receptacle to be removed therefrom, the rack which supports the receptacle is pivotally mounted on the base member 10 so that it may be pivoted about a horizontal axis in the manner illustrated in FIGURE 3. Pivotatation of the supporting rack in this manner permits the receptacle 30 to be rotated to an almost inverted position so that any material adhering to the inside thereof may be more easily removed. It should further be noted that the cross member 22 is preferably made of relatively heavy material so that when the rack and receptacle structures are moved to the position shown in FIGURE 3, the center of gravity of the entire structure acts along a line which passes through or quite close to the horizontal pivotal axis of the rack. This permits the receptacle 30 to be more easily controlled and the rack to be more easily pivoted to the FIGURE 3 position.

In referring to FIGURES 2 and 3, it will be noted that the pivotal mounting of the upright members 16 on the base 10 is such that pivotatation of the rack to the FIGURE 3 position does not appreciably lower the open end of the refuse receptacle 30. Thus, the construction employed permits the receptacle 30 to be inverted while reserving a relatively large space therebelow for the accommodation of a sizable transfer container or box 62.

After the contents of the receptacle 30 have been discharged, the supporting rack is returned to the position shown in FIGURE 2. The receptacle 30, by virtue of its relatively light weight when empty, may then be easily pivoted upwardly to its refuse receiving position illustrated in FIGURE 1. The latch means 42 is re-engaged with the bight member 48 of the U-shaped bracket 50. As the receptacle 30 reassumes the position shown in FIGURE 1, the retractable sleeve 64 moves downwardly into the receptacle and assumes the position illustrated in FIGURE 5. It will be noted that, in this position of the sleeve 64, the sleeve is unobtrusive and hidden from view, and also occupies a minimum of space within the receptacle 30. The capacity of the receptacle 30 is thus reduced to a minimum extent.

If it should be desired for any reason to remove the receptacle 30 from its supporting trunnion blocks 26, this may be easily and rapidly accomplished by extracting the pins 49 which secure the stub shafts 36 in the trunnion blocks 26 and then pulling the stub shafts outwardly to release the receptacle. This construction facilitates a relatively rapid and easily accomplished replacement of refuse receptacles which have become rusted, bent or unduly worn through extended use.

Although exemplary embodiments of the invention have been disclosed and discussed hereinbefore, it will be understood that other applications and forms of the invention are possible and that many of these will, of course, not depart from the basic principles which underlie the invention. It is therefore intended that any changes or modifications made in the structures hereinbefore described or depicted which do not depart from the basic principles underlying the invention shall be circumscribed by the spirit and scope of the invention as defined by the appended claims or reasonable equivalents thereof.

I claim:

1. Apparatus for temporarily containing refuse to be subsequently transferred to a portable container comprising:
  - a elongated refuse receptacle having an open, refuse receiving end;
  - a retractable, refuse-guiding sleeve means movably mounted in said receptacle and movable between a retracted position at least partially within said receptacle and an extended position in which a portion of said sleeve projects outwardly from the refuse receiving end of said receptacle;
  - a first stop member carried by the interior of said receptacle at a position to engage the lower portion of said sleeve to maintain the upper portion of said sleeve substantially flush with the open end of said receptacle;
  - a second stop member carried by the lower portion of said sleeve;
  - a third stop member carried by the interior of said receptacle and positioned to engage said second stop member when said sleeve is in said extended position; and
  - a rack pivotally supporting said receptacle and dimensioned to support said receptacle above the ground.
2. Apparatus as claimed in claim 1 and further characterized to include track means movable with said receptacle and cooperating with said sleeve means to facilitate gravity actuation of said sleeve means as said receptacle is pivoted on said rack.
3. Apparatus as claimed in claim 1 and further characterized to include a base member pivotally supporting said rack with the pivotal axes of said rack and of said receptacle being spaced horizontally and extending parallel to each other whereby said receptacle can be more completely emptied by pivoting both the receptacle and rack.
4. Apparatus as claimed in claim 1 wherein said refuse receptacle is cylindrical and said sleeve means is semi-cylindrical, complementary in configuration to said receptacle and mounted concentrically in said receptacle.
5. Apparatus for temporarily containing refuse to be subsequently transferred to a portable container comprising:
  - a base comprising a pair of spaced, parallel, interconnected runners;
  - a vertical, generally A-shaped upright member mounted on, and supported by, each of said runners, each of said A-shaped upright members, including a pair of legs diverging at their lower ends and converging at their upper ends, and each upright member having the lower end of one of said legs pivotally connected to the respective runner for pivotation about a horizontal axis;
  - a trunnion block carried by the upper, central portion of each of said A-shaped upright members;
  - a receptacle situated between said upright members,

said receptacle being of a diameter less than the spacing between said upright members and having an outlet formed therein at the upper portion thereof; bearing blocks mounted on said receptacle below the median portion thereof opposite each of said trunnion blocks;

a shaft extending into each pair of said trunnion blocks and bearing blocks for pivotally supporting said receptacle above said runners and between said A-shaped upright members, the horizontal pivotal axes of said A-shaped upright members on said runners extending parallel to, and being spaced vertically and horizontally from, the pivotal axis of said receptacle which extends through said trunnion blocks, said pivotal axis of said receptacle being spaced along a radius from the horizontal axis of pivotatation of said A-shaped upright members on said runners whereby pivotatation of said A-shaped upright members on said runners moves the pivotal axis of said receptacle upwardly and laterally in an arc when said A-shaped upright members are pivoted on said runners whereby the receptacle may be moved to an inverted, generally vertically extending position without moving the open end thereof closer to the ground;

stop means for preventing 180° movement of said receptacle around said shafts, said stop means comprising:

vertical legs each secured at their lower ends to said A-shaped upright members at a point vertically above said trunnion blocks; and

a horizontal member secured between said vertical legs at a position to contact the lower portion of said receptacle when said receptacle is pivoted in one direction about its pivotal axis which passes through said trunnion blocks and to contact the upper portion of said receptacle when said receptacle is pivoted in the opposite direction about its pivotal axis which passes through said trunnion blocks; and

latching means carried by said receptacle in a position to engage said horizontal member and hold said receptacle against rotational movement about said shafts.
